CLAIM

Related U.S. Application Data

The ornamental design for a while loop icon for a display screen of a programmed computer system, as shown and described.

[63] Continuation-in-part of Ser. No. 126,163, Sep. 22, 1993, Pat. No. 5,481,741, which is a continuation-in-part of Ser. No. 979,416, Nov. 19, 1992, Pat. No. 5,291,587, which is a continuation of Ser. No. 376,257, Jul. 6, 1989, abandoned, which is a continuation of Ser. No. 851,659, Apr. 11, 1986, abandoned, and a continuation-in-part of Ser. No. 380,329, Jul. 12, 1989, Pat. No. 5,301,336, which is a continuation of Ser. No. 923,127, Oct. 24, 1986, Pat. No. 4,914,568.

[51] LOC (6) Cl. 14-99

DESCRIPTION

[52] U.S. Cl. D14/114.3

FIG. 1 is a perspective view of a while loop icon for a display screen of a programmed computer system showing my new design;

[58] Field of Search .... D14/114.1–114.9; D18/28, 27; D21/13, 14, 24; D19/6; D11/95.

FIG. 2 is a front elevational view thereof; and,

99, 104, 132, 133, 165, 172; 395/155, 157,

FIG. 3 is an enlarged front elevational view thereof, with the broken-line disclosure omitted.

159

The broken-line disclosure of a computer and screen in FIGS. 1 and 2 is for illustrative purposes only and forms no part of the claimed design.
